CLAIM

The ornamental design for a package having visual indicator indicia, as shown and described.

DESCRIPTION

FIG. 1 is a front elevation view of a first embodiment of a package having visual indicator indicia according to my new design; and,

FIG. 2 is a front elevation view of a second embodiment of a package having visual indicator indicia according to my new design.

The three different stippling patterns represent a contrast in appearance. The dash-dot broken lines define the bounds of the claimed design. The claimed design extends to but does not include the defined boundary.
